The ornamental design for a combination artificial fingernails and sizing ring, as shown and described.

DESCRIPTION

FIG. 1 is a top perspective view of a combination artificial fingernails and sizing ring showing a first embodiment of our new design, wherein the nails are oval tipped;

FIG. 2 is a top plan view thereof;

FIG. 3 is a bottom plan view thereof;

FIG. 4 is a side elevational view thereof;

FIG. 5 is an enlarged fragmentary sectional view taken along line 5-5 of FIG. 2;

FIG. 6 is a top perspective view of a second embodiment of our design wherein the nails are square tipped;

FIG. 7 is a top plan view thereof;

FIG. 8 is a bottom plan view thereof;

FIG. 9 is a side elevational view thereof;

FIG. 10 is an enlarged fragmentary sectional view taken along line 10-10 of FIG. 7;

FIG. 11 is a top perspective view of a third embodiment of our design;

FIG. 12 is a top plan view thereof;

FIG. 13 is a bottom plan view thereof;

FIG. 14 is a side elevational view thereof; and,

FIG. 15 is an enlarged fragmentary sectional view taken along line 15-15 of FIG. 12.

The undisclosed edges follow the contours of the edges shown.
